Primary Examiner — Rhea Shields(74) *Attorney, Agent, or Firm* — John Rizvi; John Rizvi, P.A.—The Patent Professor®(57) **CLAIM**

I claim the ornamental design for a clinician station, as shown and described.

DESCRIPTION

FIG. 1 is a top front isometric view of a clinician station showing my new design;

FIG. 2 is a top rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

In the drawings, the broken lines are for the purpose of illustrating portions of the clinician station that forms no part of the claimed design.
